CLAIM

The ornamental design for a display screen or portion thereof with animated graphical user interface for a baccarat game, as shown and described.

DESCRIPTION

The patent or application file contains at least one drawing executed in color. Copies of this patent or patent application publication with color drawings will be provided by the Office upon request and payment of the necessary fee.

FIG. 1 is a front view of a first image of a display screen or portion thereof with animated graphical user interface for a baccarat game according to a first embodiment;

FIG. 2 is a front view of a second transitioning image thereof;

FIG. 3 is a front view of a third transitioning image thereof;

FIG. 4 is a front view of a fourth transitioning image thereof;

FIG. 5 is a front view of a fifth transitioning image thereof;

FIG. 6 is a front view of a sixth transitioning image thereof;

FIG. 7 is a front view of a seventh transitioning image thereof;

FIG. 8 is a front view of an eighth transitioning image thereof;

FIG. 9 is a front view of a ninth transitioning image thereof;

FIG. 10 is a front view of a tenth transitioning image thereof; FIG. 11 is a front view of an eleventh transitioning image thereof;

FIG. 12 is a front view of a twelfth transitioning image thereof; and

FIG. 13 is a front view of a thirteenth transitioning image thereof.

FIG. 14 is a front view of a first image of a display screen or portion thereof with animated graphical user interface for a baccarat game, according to a second embodiment;

FIG. 15 is a front view of a second transitioning image thereof;

FIG. 16 is a front view of a third transitioning image thereof; FIG. 17 is a front view of a fourth transitioning image thereof;

FIG. 18 is a front view of a fifth transitioning image thereof;

FIG. 19 is a front view of a sixth transitioning image thereof;

FIG. 20 is a front view of a seventh transitioning image thereof;

FIG. 21 is a front view of an eighth transitioning image thereof;

FIG. 22 is a front view of a ninth transitioning image thereof;

FIG. 23 is a front view of a tenth transitioning image thereof; FIG. 24 is a front view of an eleventh transitioning image thereof;

FIG. 25 is a front view of a twelfth transitioning image thereof; and,

FIG. 26 is a front view of a thirteenth transitioning image thereof.

The appearance of the image, according to the first embodiment, transitions sequentially between images shown in FIGS. 1 through 13. Whereas, the appearance of the image, according to the second embodiment, transitions sequentially between images shown in FIGS. 14 through 26. The process or period in which an image changes into another forms no part of the claimed design.

The broken lines in the drawings indicate portions of the display screen with animated graphical user interface for a baccarat game, which portions form no part of the claimed design.

With respect to FIGS. 14 through 26, any color shown on the claimed design forms no part thereof.
